(57) **CLAIM**

The ornamental design for the continuous positive airway pressure device, as shown and described.

DESCRIPTION

FIG. 1 is a front perspective view of the continuous positive airway pressure device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a view showing the use state of the present design. The broken lines showing a user, pillow, mask, and hose in FIG. 8 depict environmental subject matter which forms no part of the claimed design. All other broken lines show portions of the continuous positive airway pressure device which form no part of the claimed design.
